Germany

Filed Sept. 30, 1958, Ser. No. 53,153

Term of patent 14 years

(Cl. D61—1)

FIG.1

FIG.2

Fig. 1 is a perspective view of an optical objective embodying my novel design; and

Fig. 2 is a top plan view of same.

The side opposite that in Fig. 1, not shown, is substantially a mirror image of Fig. 1 with the exception of the window openings. The broken-line showing of legible matter in Fig. 1 is for illustrative purpose only. A portion of the drawing figure is diagonally lined to indicate transparency.

I claim:

The ornamental design for an optical objective, as shown and described.
